ABSTRACT

The arc tube of a metal halide arc discharge lamp contains a gaseous filling of about 60% argon — 40% neon.

1 Claim, 1 Drawing Figure

ARC DISCHARGE LAMP HAVING REDUCED STARTING VOLTAGE

BACKGROUND OF THE INVENTION

1. Field of the Invention

This invention relates to high intensity metal halide arc discharge lamps of the type used for general illumination. Such lamps have a generally cylindrical arc tube having electrodes at each end thereof. The arc tube contains a fill of mercury, metal halide and, for starting purposes, an ionizable gas. During normal operation, the pressure within the arc tube is between about one to ten atmospheres and the arc tube temperature is between about 450° and 900°C.

2. Description of the Prior Art

Metal halide arc discharge lamps for general illumination have become commercially useful in the past five to ten years because they are more efficient and yield a whiter light than high pressure mercury vapor lamps. The construction and operation of metal halide lamps are shown in the *IES Lighting Handbook*, 5th ed. N.Y., Illuminating Engineering Society, 1972, p. 8-34.

The arc tube of such lamps contains an inert, ionizable gas for starting purposes; the gas usually is argon.

It is known that mixtures of gases, so-called Penning mixtures, can reduce arc tube starting voltages to a lower value than that of single component gas fills. The reason for this is discussed in Waymouth, J. F. *Electric Discharge Lamps*. Cambridge, Mass. & London, England, The M.I.T. Press, 1971, p. 63-67.

In a Penning mixture, one gas is present in a small quantity and the other gas is present in a larger quantity, usually at least about twenty times the amount of the first gas. Examples of such mixtures are shown in U.S. Pat. Nos. 2,176,134 and 3,753,018.

SUMMARY OF THE INVENTION

A metal halide lamp in accordance with this invention comprises an arc tube, usually made of high temperature glass, such as silica, having tungsten electrodes at each end thereof and containing a fill including mercury, a light emitting metal and halogen in the halide form. The arc tube also contains a gaseous filling of neon and argon for starting purposes. The neon-argon mixture is outside the composition of a Penning mixture. Minimum starting voltage is obtained at a composition of about 60% argon and 40% neon by volume.

BRIEF DESCRIPTION OF THE DRAWING

The single FIGURE in the drawing is an elevational view of a metal halide arc discharge lamp in accordance with this invention.

DESCRIPTION OF THE PREFERRED EMBODIMENT

As shown in the drawing, a metal halide lamp in accordance with this invention includes a generally tubular outer bulbous envelope 1 having a bulbous central portion and a conventional base 14 attached to the bottom thereof. Extending inwardly from the base and inside of the envelope 1 is a mount 15 having a pair of stiff lead-in wires 12 and 16 in electrical conducting relation with the base 14. Disposed upon one of the stiff lead-in wires 12 is a lower, U-shaped support 8 welded thereto. U-shaped support 8 comprises a pair of verti-

cal wires 23 and 24 rising from a horizontal base wire 25. The upper ends of lower U-shaped support 8 are welded together with a lower strap 7 which in turn supports an arc tube 2. Preferably, the lower strap includes

5 two sections abutting against either side of arc tube 2 thereby holding it firmly in place. They touch only the press seal of the arc tube and not the body. Generally, both sides of the lower strap 7 can be of identical construction. A pair of bumpers 26 are welded to lower U-
10 shaped support 8 and abut against the tubular portion of the walls of outer bulbous envelope 1, thereby stabilizing the structure within the lamp. Preferably, these bumpers are made of a resilient material so that if the lamp is jarred they will absorb much of the shock.

15 Since lower U-shaped support 8 is electrically connected to stiff lead-in wire 12, support 8 forms part of the circuit in the device. Current passes from base 14 into lower U-shaped support 8 and thence to lead-in wire 21 which in turn is connected to electrode 4 in the arc tube. It is sometimes desirable to place an insulating shield about lead-in wire 21 to prevent arcing within the lamp and between the various elements. Current passes from lead-in wire 21 to electrode 4 through an intermediary molybdenum foil section 6.

20 25 The other side of the circuit is formed through stiff lead-in wire 16 which is preferably bent out of place so that parts on one side of the line are insulated from those on the other side. A resistor 13 is attached to stiff lead-in wire 16 through a lead-in wire associated therewith and thence to a connector 27 which in turn leads through a molybdenum foil section 6 to a starting probe 5. A bimetal 22 is disposed between lead-in wire 21 attached to electrode 4 and connector 27 which is attached to starting probe 5. Bimetal 22 is biased open 30 when the lamp is turned off but when the lamp starts, it biases closed against the lead-in wires to probe 5 thereby establishing the same electrical potential at probe 5 and electrode 4. Such closing prevents electrical discharge between the probe and electrode.

35 40 At the other end of arc tube 2, an upper support 10 is mounted within the tubular portion of bulbous envelope 1. Support frame 10 includes a horizontal section 18 having vertical supports 17 and 19 depending downwardly therefrom and attached at the free ends to an upper strap 11 which surrounds the press seal of arc tube 2 and rigidly holds it in place. Preferably, the construction and deposition of upper strap 11 is similar to lower strap 7. A pair of upper bumpers 9 are mounted upon vertical sections 17 and 19 of upper support 10 and resiliently abut against the sides of the tubular portion of bulbous envelope 1. Such disposition prevents breakage of the arc tube if the lamp is shaken or dropped.

45 50 55 A lead-in wire 28 extends to the outside of arc tube 2 and is attached at its inner end to a molybdenum foil section 6 and thence to electrode 3. An electrical connection is made between stiff lead-in wire 16 and lead-in wire 28 through a thin conducting lead 20 which may be of any suitable conducting material. Preferably, conducting lead 20 is distantly removed from arc tube 2, generally by bending it close to the perimeter of outer bulbous envelope 1.

60 65 Disposed within arc tube 2 is an inert starting gas mixture of neon and argon, and a fill which includes mercury, halogen and a light emitting metal. The light emitting metal can be one or more of scandium, sodium, thorium, thallium, indium or any light emitting

metal commonly used in metal halide lamps and can be added in element or compound form. The halogen, usually iodine, is generally added as a metal halide. Mercury is present in the usual amount, that is to say, so that under normal operating conditions, the mercury is totally vaporized and produces a pressure within arc tube 2 of about 1 to 10 atmospheres.

The starting gas mixture of neon and argon is outside the composition of a Penning mixture and is, preferably, for minimum starting voltage, about 60% argon and 40% neon.

Starting voltage was determined for 400 watt metal halide arc discharge lamps containing a fill of mercury, sodium iodide and scandium iodide and containing a starting gas filling at 35 torr of various mixtures of neon and argon. For lamps at room temperature, starting voltage at mixtures of 100% argon, 80% argon-20% neon, 60% argon-40% neon, 40% argon-60% neon, 20% argon-80% neon and 100% neon were, respectively, 315 volts, 290 volts, 245 volts, 295 volts, 300 20 volts and 260 volts, using a sine wave reactor. At -20°F, using a ballast, the starting voltages for the same mixtures were, respectively, 270 volts, 250 volts, 235 volts, 265 volts, 345 volts and 335 volts. In both cases, the lowest starting voltage occurred at a gas composition of about 60% argon-40% neon.

An advantage of this invention lies in the fact that it permits use of higher gas fill pressures than are normally used in metal halide lamps, without significant increase in starting voltage. Higher gas fill pressures are desirable since they improve lamp maintenance by reducing electrode sputtering during lamp warm-up. The change in starting voltage versus gas fill pressure was as follows: for argon fill alone, room temperature starting voltage was 257 volts at 35 torr and 270 volts at 50 torr. In contrast, for 60% argon-40% neon, starting voltage was 260 volts at 35 torr but decreased to 250 volts at 50 torr. Similarly, at -20°F., starting voltage for argon

alone was 300 volts at 35 torr and increased to 343 volts at 50 torr; for 60% argon-40% neon, starting voltage was 293 volts at 35 torr and only 295 volts at 50 torr.

The improvement in starting voltage continued throughout the life of the lamps. For example, after 6400 hours of operation, the average starting voltage for prior art lamps, which had a gas fill of argon at 35 torr, was 271 volts. In contrast, the starting voltage for lamps in accordance with this invention after 6400 hours of operation was lower, even at gas fill pressures as high as 80 torr. The results were as follows: for gas fill of 60% argon-40% neon at 50 torr, average starting voltage after 6400 hours was 247 volts; for the same gas fill at 60 torr, the same starting voltage was 253 volts; for the same gas fill at 80 torr, the same starting voltage was 263 volts.

Another advantage of the gas fill of this invention results from the lower quantity of neon of neon the arc tube gas fill mixture as compared with the quantity of neon in a Penning mixture. As mentioned in the previously cited U.S. Pat. Nos. 2,176,134 and 3,753,018, neon can diffuse through the walls of arc tube 2, thus requiring the filling of outer envelope 1 at least partially with neon. But neon has a higher heat conductivity than other gases, such as nitrogen, normally used in the outer envelope and can thus lower lamp efficiency by cooling the arc tube more than said other gases. The lower neon content of the gas mixture of this invention requires less neon in the filling of outer envelope 1.

We claim:

1. A high intensity metal halide arc discharge lamp comprising a sealed arc tube having electrodes at each end thereof and containing a fill including mercury, metal halide and a starting gas filling, said filling comprising a mixture of about 60% argon-40% neon.
